UNITED STATES PATENT OFFICE.

GEORGE A. PARKER, OF HARTFORD, CONNECTICUT, ASSIGNOR OF ONE-HALF TO
FRANKLIN C. WHITMORE, OF WEST HARTFORD, CONNECTICUT.

PARK-BENCH.

1,154,268.

Specification of Letters Patent. Patented Sept. 21, 1915.

Application filed April 3, 1913. Serial No. 752,578.

To all whom it may concern:

Be it known that I, GEORGE A. PARKER, a citizen of the United States, residing at Hartford, in the county of Hartford and 5 State of Connecticut, have invented a new and useful Improvement in Park-Benches, of which the following is a specification.

This invention relates to a bench which is primarily intended to be placed in a public park to afford workmen and laborers a convenient and sociable settee and table for use at lunch time, although of course it can be placed in private as well as public parks and may be used by picnickers or 15 others desiring a comfortable resting place with convenient facilities for writing or supporting a book or handiwork.

The object of this invention is to provide a simple and cheap open air bench which 20 will accommodate two people and provide both with convenient table facilities and at the same time so divide the bench that one party cannot dispose himself in such manner as to occupy all of it, or cannot use 25 it for sleeping purposes. In accomplishing this object a bench is built with a back on one side near one end and with a back on the other side near the other end, and provided with a table that extends angularly 30 between, is supported by and assists in strengthening the backs, the table being shaped to give sufficient surfaces arranged in convenient positions for holding lunches, papers, magazines, books or work for two 35 people, and the seat being cut away on each side to permit persons occupying opposite ends and facing oppositely on the bench to turn somewhat sidewise toward each other without inconvenience when desiring to 40 utilize the table or converse.

Figure 1 of the accompanying drawings shows a plan of a park bench which embodies this invention. Fig. 2 shows a front view of the same. Fig. 3 shows an end view, 45 and Fig. 4 shows a bottom view.

The frame, legs and back supports of this bench may be constructed of either metal or wood, desirably the latter, as illustrated in the drawings and hereinafter described.

50 The frame which is shown is built of transverse pieces 1, longitudinal pieces 2 and diagonal braces 3, fastened together in any suitable way so as to form a stiff oblong structure. The upper ends of the four legs 55 4 are secured in the corners of the frame.

The seat is formed of strips 5 that are fastened to the top of the frame and are suitably spaced apart to form a comfortable resting place which will not retain water. A section of the seat along one edge at one 60 side of the middle, and a similar section along the other edge at the other side of the middle is recessed, as at 6, so as to make it somewhat narrower at those localities. The lower ends of the back supports 7, are fastened to the frame, those on one side of the middle being on one side of the seat and those on the other side of the middle being on the other side of the seat. These supports desirably incline outwardly from each 65 other. Fastened to these supports on each side are the back rails 8 and 9. If the frame and back supports are made of wood, the outer back supports may be strengthened by metal bracket plates 11. 70

Arranged across the bench at a little distance above the seat is a table 10. This table is supported by and fastened to the projecting inner ends of the lower back rails 9 on opposite sides, and it is also fastened 75 to the inner of the two back supports on the opposite sides of the seat so as to hold those supports from being spread apart and broken off. The table is desirably made somewhat narrower at the middle than it 80 is at each outer end and the ends are swelled on the sides of the seat opposite from the backs, that is, the table is rounded out so it will extend partly in front of a person 85 sitting on the bench and leaning against the back on either side. The recessed sections of the seat are made beneath the table so that persons may turn sidewise when using the table without inconvenience. 90

A strong bench can be cheaply built in 95 the manner described, and can be placed in public or private parks by municipalities, corporations or individuals for the comfort of laborers and workmen during lunch time. The table affords convenient support for 100 lunches, writing materials, or a book. The table is supported by the back rails and at the same time it ties the backs together and prevents them from being broken off, and while having the functions of a table and of 105 strengthening means it divides the bench so that two parties can occupy it comfortably without too close contact. The table also prevents one person from monopolizing 110 the bench or any one from using it for sleep-

ing purposes, as benches are frequently utilized in warm weather in public parks.

The invention claimed is:

1. A park bench having a frame, legs supporting the frame, a seat fastened to the frame, a back on one side of the frame near one end of the seat, a back on the other side of the frame near the other end of the seat, and a table supported by and tying together the inner ends of the backs, said table on each side extending beyond the back by which it is supported and in front of the back on the opposite side.
2. A park bench having a frame, legs supporting the frame, a seat fastened to the frame, a back on one side of the frame near one end of the seat, a back on the other side of the frame near the other end of the seat, a table supported by and tying together the inner ends of the backs, said table on each side extending beyond the back by which it is supported and in front of the back on the opposite side, and said seat being recessed at the front edges beneath said projecting portions of the table.
3. A park bench having a frame, legs supporting the frame, a seat fastened to the frame, two backs, one fastened to one side of the frame on one side of the middle and the other fastened to the other side of the frame on the other side of the middle, and a table supported by and tying together the inner ends of the backs, said table extending obliquely with relation to the seat and to

the backs and projecting on each side beyond the edge of the seat and in front of the back on the opposite side.

4. A park bench having a frame, legs supporting the frame, a seat fastened to the frame, two back supports fastened to one side of the frame at one side of the middle and two back supports fastened to the other side of the frame at the other side of the middle, back rails fastened to the back supports, and a table supported by the back rails and tying together the inner ends of the backs, said table extending diagonally across the seat and projecting on each side beyond the edge of the seat and in front of the back on the opposite side.

5. An open air bench having a frame, four legs supporting the frame, seat strips fastened to the top of the frame, back supports on opposite sides of the frame on opposite sides of the middle, back rails connecting the back supports, a table extending between and secured to the inner back supports and supported by the back rails, said table projecting on each side over the edge of the seat in front of the back that is on the opposite side, and said seats being recessed on the edges beneath the projecting portions of the table.
